UNITED STATES PATENT OFFICE.

WILLIAM CALAM, OF BRIDGEPORT, CONNECTICUT, ASSIGNOR OF ONE-HALF
TO THE COULTER & MCKENZIE MACHINE COMPANY, OF SAME PLACE.

OYSTER-DREDGE.

SPECIFICATION forming part of Letters Patent No. 394,333, dated December 11, 1888.

Application filed September 27, 1888. Serial No. 286,521. (No model.)

To all whom it may concern:

Be it known that I, WILLIAM CALAM, a citizen of the United States, residing at Bridgeport, in the county of Fairfield and State of Connecticut, have invented certain new and useful Improvements in Oyster-Dredges; and I do hereby declare the following to be a full, clear, and exact description of the invention, such as will enable others skilled in the art to which it appertains to make and use the same.

My invention has for its object to so improve the construction of dredges as to render it practically impossible in either casting or hauling to turn the dredge bottom upward. In order to accomplish this result in a simple and economical manner, I have devised the novel construction of which the following description, in connection with the accompanying drawings, is a specification, numbers being used to denote the several parts.

Figure 1 is a plan view; Fig. 2, a rear elevation thereof, the bag being removed in both views, as it forms no portion of my invention. Fig. 3 is a detail view showing in side elevation the neck of the dredge, and Fig. 4 is a longitudinal section of the dredge complete.

1 denotes the blade, which is ordinarily provided with teeth 2. The frame-work of the dredge consists of bifurcated arms 3, which are held securely in position by braces 4. In practice these parts are made of steel, are preferably made square, and are secured together by rivets 5 instead of by welding, as has heretofore been the custom. I thus secure the maximum amount of strength, and at the same time am enabled to take the dredge to pieces should repairs be necessary. This avoids lifting and handling the entire dredge, and also the danger of destroying the quality of the metal, as is unavoidable in repairing dredges made by welding the parts together.

6 denotes a cross-piece extending between the upper branches of the bifurcated arms. At the neck of the dredge the branches of the arms unite, and the arms themselves are united by bolts or rivets 7.

A stay-piece (denoted by 8) is preferably placed between the arms and assists in strengthening the neck of the dredge, the rivets or bolts passing through both of the

arms and the stay-piece. At the rear end of the stay-piece I preferably form an eye, 9, which is engaged by a bifurcated longitudinal brace. The upper branch of this brace (denoted by 10) engages cross-piece 6, and the lower branch, (denoted by 10^a) is passed through the blade and secured in position by a nut, 11. The upper branches of arms 3 are connected to the blade by braces 12, which are outwardly curved, the greatest width between the braces from side to side being at a point considerably nearer cross-piece 6 than the blade. (See Fig. 2.) By constructing braces 12 in this manner I insure that one of the curves, which I denote specifically by 12^a, in casting or hauling, will come in contact with the bottom of the sea or the side of the vessel.

It will of course be apparent that the bottom of the dredge is much heavier than the top, and that by placing curves 12^a above the mid-length of the braces I increase the leverage of the bottom of the dredge, and thus make it practically impossible in casting or hauling to make the dredge strike the bottom of the sea or the side of the vessel in such a manner that the weight of the bottom of the dredge, assisted by the leverage produced by one of the curves 12^a, will not instantly turn the dredge right side upward. This is a very important feature, for the reason that as dredges have heretofore been constructed, unless they were cast with the greatest care, they were quite as likely to strike bottom upward as otherwise. Likewise, in hauling they were extremely likely to turn bottom upward upon striking the side of the vessel, thus necessitating that the dredge, weighing several hundred pounds and containing from fifteen to twenty-five bushels of oysters, be lifted over by hand, or else that the dredge be sunk time after time, and the boat swung about here and there until the dredge could be turned right side up.

I have not shown the bag in which the oysters are caught, as it seems wholly unnecessary. It is sufficient to say that the bag is secured in the usual or any preferred manner to cross-piece 6, to the braces 12, and to the bottom cross-piece, 13, which extends from side to side just back of the blade, its ends

being held by brackets 14. In the drawings I have shown braces 12 as made continuous with the upper branches of arms 3. In practice I ordinarily provide the ends of cross-piece 5 with eyes 15, through which the upper branches of the arms pass, said arms being then curved outward and downward to form braces 12, the lower ends of said braces being riveted or bolted to the blade, as are also the rear ends of the lower branches of arms 3.

I preferably provide a single heavy bolt, 16, at each side of the dredge, which passes through the rear end of the lower branch of the arm, then through the blade, then through 5 the lower end of the brace 12, an eye being formed for that purpose, and then through bracket 14, the whole of these parts being locked in position by a nut, 17.

It is found in practice that the outward curve of braces 12 gives a greatly-increased opening at the mouth of the bag, which assists materially in dumping; that the shape gives strength and rigidity to the dredge as a whole; and, furthermore, when the dredge is used for star-fishing, that it enables the ordinary star-frame to be folded within the dredge in dumping, which is impossible as the side braces are ordinarily constructed, and is a source of great inconvenience. Another important feature of my improved construction is that I curve the neck of the dredge outward to correspond with the side of the vessel upon which it is to be used, these dredges being always used in pairs, the neck of the dredge to be used upon the starboard side of the vessel being curved toward the right, and the neck of the dredge to be used on the port side being curved toward the left. The object of this construction is to throw the line 5 of draft outward in hauling, so that the greater portion of the weight of the dredge and of the catch lies within the line of draft.

It will of course be understood by those familiar with oyster-dredges that in hauling dredges as heretofore constructed the outer side is dragged down by its own weight and that of the catch, so that unless the boat is turned about the dredge breaks water at an angle and is very apt to turn over. I have 5 found that by curving the neck of the dredge outward, thereby throwing the line of draft outward and greatly increasing the weight within the line of draft, I cause the two sides

of the dredge to rise evenly, or so nearly so as to render it unnecessary to turn the vessel in 55 the slightest in hauling.

Having thus described my invention, I claim—

1. An oyster-dredge comprising arms having upper and lower branches, a neck, and a 60 blade, the branches of said arms being connected by braces having outward curves, 12^a, near the upper portion thereof, whereby the weight of the bottom of the dredge is given increased leverage when either of the curves 65 strikes the bottom of the sea or the side of the vessel and renders it impossible to turn the dredge bottom upward.

2. An oyster-dredge comprising arms with upper and lower branches, a blade, and upper 70 cross-piece having eyes at its ends, the rear ends of the upper branches passing through said eyes and then curving outward and downward, forming braces having curves 12^a, the ends of both upper and lower branches being 75 riveted to the blade.

3. An oyster-dredge comprising a blade, a cross-piece, 6, and arms having upper and lower branches, the rear ends of the upper branches being curved outward and downward, for the purpose set forth, and the ends of all of the branches riveted to the blade, a stay-piece between the forward ends of the arms, and bolts passing through the arms and stay-piece. 85

4. An oyster-dredge comprising a blade, a cross-piece, 6, arms having upper and lower branches, braces 12, connecting the upper branches to the blade, a stay-piece riveted between the forward ends of the arms, and a bifurcated longitudinal brace whose forward end is connected to the stay-piece, the rear ends of the branches being connected, respectively, to the cross-piece and to the blade. 90

5. An oyster-dredge having its neck curved 95 outward to correspond with the side of the vessel upon which it is to be used, so that in hauling the greater portion of the weight will fall within the line of draft, as and for the purpose set forth.

In testimony whereof I affix my signature in presence of two witnesses.

WILLIAM CALAM.
